UNITED STATES PATENT OFFICE.

MERRILL DAVIS, OF WATERTOWN, NEW YORK, ASSIGNOR TO JAMES B. WISE, OF WATERTOWN, NEW YORK.

PORTABLE FURNACE.

1,008,406.

Specification of Letters Patent. Patented Nov. 14, 1911.

Application filed September 1, 1911. Serial No. 647,181.

To all whom it may concern:

Be it known that I, MERRILL DAVIS, citizen of the United States, residing at Watertown, in the county of Jefferson and State of New York, have invented certain new and useful Improvements in Portable Furnaces, 5 of which the following is a specification.

This invention relates to improvements in portable furnaces, designed for use in melting various kinds of metals, the furnace being 10 tiltable and rotatable for pouring the metal directly into the molds.

The invention relates particularly to improvements in the devices shown and described in my former applications, filed respectively, March 30, 1911, Serial No. 617,874, and July 13, 1911, Serial No. 638,296.

The object of my invention is to provide 20 a tiltable and rotatable furnace for melting metal, which may be readily transported from place to place, and which carries its own heating agent.

A further object is to provide a furnace 25 which is adapted for pouring the molten metal directly into the molds, without disturbing the fire, or requiring the rehandling of the metal.

A further object is to provide a plurality 30 of simultaneously actuated hoisting devices for supporting and elevating the furnace.

A further object is to provide adjustable means for varying the axis upon which the 35 pouring spout of the furnace rotates, so as to deposit the metal at different points successively, without disturbing the furnace or its operating parts.

A further object is to provide simple means for effecting the automatic raising of 40 the pouring spout during the final pouring operations, for the purpose of "feeding" the molds. And a further object is to provide means capable of manual, and also automatic operation, for controlling the hoisting devices.

The various features and parts of my invention will be described in the subjoined specification, illustrated by the accompanying drawings, and then particularly pointed 50 out in the appended claims.

Figure 1 is a top plan view of the device; showing the furnace in erect position ready for charging and firing. Fig. 2 is a front elevation of the same. Fig. 3 is a right side 55 elevation of the furnace in erect position.

Fig. 4 is a right side elevation; showing the furnace tilted for skimming the metal preparatory to pouring the same into the molds. Fig. 5 is a similar elevation; showing the furnace in elevated position; also showing the method and means for elevating the pouring spout during the pouring operation. Fig. 6 is a view similar to Fig. 5; showing furnace in elevated position; also showing the method and means for shifting the pouring spout horizontally for depositing the metal at different points. Fig. 7 is a central longitudinal section through one of the hoisting devices. Fig. 8 is a cross-sectional view of the valve which controls the hoists; the valve being closed. Fig. 9 is a similar view; showing the valve open. Fig. 10 is a similar view; showing the valve reversed for exhausting the air pressure from the hoists.

Similar characters of reference are assigned to corresponding parts throughout the several views.

After devising and putting into practice my former furnaces referred to in the said applications, I found that the provision of a fixed, unvarying point from which the melted metal is to be poured, had the effect to limit the said furnaces to but a few classes of foundry work, where it is desirable to pour the metal direct from the crucible into the molds, and that one or more important branches of the casting business, as it obtains in the rolling-mills, could not be handled by the said furnaces, principally because of the feature of the fixed point for pouring the metal.

In rolling-mill practice, the rods or ingots from which wire and tubes are formed, are cast in iron molds which are placed in substantially vertical position, and the molten metal is poured into the top ends of the molds. These ingots are usually of comparatively small diameter, and quite long, and the melted metal must be poured into the molds as rapidly as possible until the molds are full. Should the pouring operation be stopped when the molds are full, a crust would immediately form over the tops, and the rapid shrinking of the metal would cause flaws and cracks or initial strains, which would render the ingots unfit for use. This tendency is overcome by a process commonly known as "feeding", which will be briefly described: When the mold has been 110

oured full, the flow of the metal is suddenly reduced to a stream about the size of a common lead pencil, which is allowed to gravitate into the top of the mold. At the same time, the point or spout from which the metal is poured is raised to a greater height, in order to give this small stream sufficient velocity to continually break through the crust which rapidly forms on the top of the 10 poured metal. The size of this "feeding" stream is regulated by the rate at which the metal in the mold shrinks or contracts, and when the shrinking and contracting has ceased, the pouring is stopped. This condition and requirement, I have found, renders a furnace that pours the metal from a fixed point useless for this class of rolling-mill work. To this end, I have redesigned the furnaces of my former applications, and 20 have provided means whereby the pouring spout may be moved horizontally and also vertically within a certain range, for depositing the melted metal at different points, as well as, from a higher level or plane, and the 25 said adjustment may be effected either before, or during the pouring operations, without in any way interfering with the pouring of the metal. The adjusting parts may also be set to cause automatic action of the pouring spout controlling-mechanisms as the different periods or stages of the pouring operations are reached, and the degree or range of the said variations can be instantly 30 changed to meet unexpected requirements or 35 miscalculations.

The furnace comprises a hollow cylindrical outer body or shell 2, in which is disposed a crucible or melting-pot 3, which may follow the usual construction, and may be 40 held in place by any suitable means.

4 represents a pouring spout, which is preferably attached to the top of the body 2, at one side of the crucible, in position to receive the contents of the crucible when the 45 furnace is tilted. The crucible is preferably disposed centrally in the body 2, and is surrounded by a combustion chamber 5, in which any suitable fuel, such as gas, oil or coke may be placed and burned for heating 50 the furnace. The fuel may be burned under natural or mechanical draft, applied in any suitable manner.

The self-contained furnace is fitted with trunnions 7 and 7', which are preferably 55 rigidly attached to the opposite outer sides of the body 2, by means of which the entire weight of the furnace is supported. Each of the trunnions is journaled in bearings which are formed in like integral perforated 60 lugs or projections 9, of the outer movable members 10, of a pair of hoisting cylinders A and A', which reciprocate on inner members or plungers 11 of the hoists. The 65 plungers 11 extend below the lower ends of the cylinders 10 and are pivotally supported

by a common shaft 12, which is journaled in and supported by suitable bearings 13 forming parts of the end portions 14 of the truck frame, in such manner that the hoists A and A' may oscillate slightly during their operations.

Fig. 7 illustrates the construction, arrangement and operation of one of the hoisting devices, which will now be described: The cylinder 10 telescopically fits over the plunger 11, there being a clear space or chamber 15 arranged between these parts, which is intended to be normally filled with oil or other suitable liquid for braking and steadyng the cylinder 10 during its reciprocating movements. A suitable packing 16 is disposed within each end of the cylinder 10, for preventing the escape of the oil from the chamber 15. Any suitable means may be employed for compressing and holding the packing 16 in place, but the lower packing 16 is preferably provided with an upper gland 17, which comprises a tubular part, the upper end of which projects into the chamber 15. The gland 17 is so arranged, that when the cylinder 10 moves upwardly over the plunger 11, the said gland forces the oil in the chamber 15 through a port 18, into an inner oil chamber 19, which is formed in the plunger 11. Both of the chambers 15 and 19 are intended to be filled to their capacity with a heavy oil, the oil being supplied in the first place by means of a threaded hole 15' in the cylinder 10, which is then closed by a screw-plug 15''. The plunger 11 is preferably hollow throughout its entire length, and its interior is lined with a tube 20, which is preferably fitted liquid tight into the opposite ends of the plunger. The tube 20 forms the inner side 10 of the oil chamber 19. Below the tube 20, the opening through the plunger is closed by a plug 21, which is held tightly in place by a screw 21', the said plug having an upwardly projecting nozzle-like part 22, which is bored out for carrying oil into the interior of the tube 20 during the operation of the hoist. Within the tube 20 is disposed a piston 23, which is provided with a packing 23', which is compressed between a gland 24 and a flange 25. 26 represents the piston rod, the lower end of which connects to the piston, while the upper end is adjustably connected to a cap 27, which is secured to the upper end of the cylinder 10 by bolts 27'. The upper end of the rod 26 is threaded for receiving an adjusting-nut 28. 29 represents a tube which surrounds the piston rod, its lower end bearing upon the gland 24, the upper end of said tube interfiting with the underside of the cap 27. The arrangement of these parts is such that, when the nut 28 is screwed down on the rod 26, the piston is raised, and owing to the presence of the tube 29, which bears against 130

the gland 24, the packing 23' is compressed. 30 represents a port in the upper end of the cylinder 10, for admitting air pressure carried by a pipe 31, for operating the hoist. 5 The pipe 31 is preferably flexible, and connects at its other end with a valve 32, which is employed for controlling the hoists A and A'. When the compressed air is admitted into the top of the cylinder 10, the 10 said cylinder will move upwardly along the plunger 11, and at the same time the gland 17 in the bottom of said cylinder moving upwardly in the chamber 15, displaces the oil therein and forces it through the port 15 18 into the chamber 19. The oil being incompressible, must have an outlet from the chamber 19, which is already full of the fluid, and for this purpose, I provide a port 33 at the bottom of said chamber, which 20 connects with a pipe 34, which carries the oil to the valve 32. The oil then passes through the valve 32 and returns by way of a flexible pipe 35 and re-enters the lower end of the plunger 11, by way of a port 36, which 25 extends through the wall of the plunger and into the plug 21, where it rises in the nozzle 22. The nozzle 22 is disposed in a hollow part 36' of the piston 23, the outside of the nozzle is formed tapering, and the 30 whole of this part is smaller in diameter than the chamber 36' of the piston, so that the oil flows freely out of the top of the nozzle, thence downwardly into a small chamber 37 disposed below the piston 23. As 35 soon as the cylinder 10 begins to move upwardly, the chamber 37 increases in depth, and this space is immediately filled with the oil which has been displaced from the chambers 15 and 19. The space between the plug 40 21 and the piston 23 which comprises the chamber 37 is intended to be exactly proportioned to the decreasing capacity of the chamber 15, so that the quantity of oil forced out of the chamber 15 will all be taken up 45 by the chamber 37. In this manner the piston 23, as well as the cylinder 10, while reciprocating, are in direct contact with the body of oil in the chambers 15 and 37, and in case the air pressure should fail for any 50 reason, while the hoist is in the elevated position, the body of oil confined in the several chambers will prevent the violent descent of the cylinder 10. The speed at which the cylinder 10 may be raised or lowered is 55 regulated by the area of one or all of the several ports or passages through which the oil must flow in passing to and from the chambers 15 and 37. By the use of the oil, as described, the hoists are always kept 60 under complete control, and the rate of travel of the cylinders 10 is at all times governed by the rate of flow of the oil.

The valve 32 which controls the hoists will now be described.

65 40 represents the outer casing or shell of

the valve, in which is rigidly fitted a bushing 41, which is bored out tapering to fit the tapering plug 42. The said plug is provided with a cylindrical portion 43, which is preferably fitted tightly into one end of 70 a link 44, the outer end of the part 43 then passes loosely through and pivots in the upper end of a lever 45, the said link and lever forming parts of the elevating mechanism of the furnace. The casing 40 is provided with threaded radial ports or holes a, b, c and d, into which are screwed pipes 31, 34, 35 and 46, employed for conducting air pressure and oil to and from the valve. The bushing 41 is provided with a number of 75 longitudinal slots or ports a', b', c' and d', each of which communicates at or near one end with the ports of the casing 40. The casing 40 is provided with a laterally projecting portion 47, which is bored out to 80 form a socket to receive one end of an operating handle or lever 48, by means of which the casing is manually operated. 49 represents a threaded hub formed on the opposite end of the plug 42, which pierces the 90 center of a four-arm spring 50, which is held in place by a nut 51. The spring 50 is employed for holding the casing 40 operatively engaged with plug 42.

The operation of the valve 32 is as follows: Air pressure from any suitable source is supplied to the valve through pipe 46. When the valve parts are in the position shown in Fig. 8, no air or oil can pass through the valve. When the operator pulls downwardly on the hand-lever 48, the casing 40 will be rotated to the left, from the position shown in Fig. 8, to that shown in Fig. 9, which will bring the ports a' and b' into communication with curved passage f 95 of the plug 42, which will allow the air pressure to flow from the pipe 46 into the pipe 31, to be carried by the latter to the hoisting cylinder A. At the same time the air ports 100 are opened, as described, the ports c' and d' on the opposite side of the casing 40, are brought into communication with an irregularly formed by-pass h in the plug 42, which allows the oil entering the valve 105 through the pipe 34 to pass into the pipe 35 to be returned to the hoist.

The foregoing describes the operation of the valve for effecting the raising of the hoisting cylinders 10 by the air pressure, and also the shifting of the oil carried by 110 the chambers 15 into the chambers 37 for the braking and steadyng of the hoists. In order to effect the reverse operation of the hoists, the air must be exhausted from the cylinders 10, so as to permit the weight of 115 the hoist and of the object lifted, to close the telescoping parts 10 and 11. To exhaust the air, the operator should swing the lever 48 to the right sufficiently to shift the casing 40 to the position shown in Fig. 10, which 120

125 130

will close the curved passage *f* of the plug, and bring the port *b'* into communication with a radial passage *j*, which connects with a central port *k*, which communicates with the atmosphere through the center of the threaded hub 49. When the parts are brought into the last position, the air pressure confined in the cylinders 10 of hoists A and A' will escape to the atmosphere through the port *k*. At the same time the casing 40 is rotated for exhausting the air, the oil ports *c'* and *d'* will be brought into communication with the by-pass *h* of the plug 42, which will allow the free passage of the oil from the chamber 37 of the hoist through pipe 35 into the said by-pass, thence returning to the chamber 15, by way of the pipe 34, chamber 19 and the port 18. As the air is exhausted, the hoists A and A' will close down gradually, the closing movement, like the opening movement being regulated by the rate of flow of the oil, as described. In order to provide for the simultaneous circulation of the oil from the valve 32 to both of the hoists, the pipes 31, 34 and 35, are each provided with T's 52, to which are connected branch pipes 31', 34' and 35'; all of the latter pipes connecting with the hoist A' in exactly the same manner as is shown for the hoist A.

The truck frame comprises the end rails or parts 14, and the side rails 14', which may be joined together in any suitable manner. The truck is provided with four wheels or rollers 53, which are journaled on short gudgeons of pins 53', which are embedded in the side rails 14' of the frame. The truck preferably travels on track-rails 54.

The mechanism for elevating and controlling the furnace consists of the following parts: 55 represents rearwardly projecting perforated lugs carried by cylinders 10 of the hoists, which are preferably located opposite the lugs 9, to which are pivotally connected downwardly extending levers 56, by means of pins 56'. The lower ends of the levers 56 are pivotally connected to like side levers 57, by pins 57'. The forward ends of the levers 57 are pivotally attached to upwardly extending portions of the frame 14-14' by means of a common shaft 58, which extends across the front of said frame.

When the furnace is tilted from the position shown in Figs. 1, 2 and 3 to that shown in Fig. 4, and also during its elevation for pouring the metal, the top of the furnace is supported by two three-arm levers 59, disposed one on each side of the body 2. One arm 59' of the said lever is pivoted to the trunnions 7 and 7'. The forward arms 60 are pivoted to the upper ends of levers 61, by pins 61', the lower ends of the levers 61 being pivotally connected to the side levers 57 by means of a shaft 62, so that the levers

61 are adapted to move upwardly and downwardly with the levers 57.

63 represents the short upper arms of the levers 59, which are slotted at 63' to receive pins 64 and 64', which are made fast to the opposite sides of the body 2, and which slide back and forth in the said slots while the furnace is tilted or rocked on the trunnions 7 and 7'. The pin 64 is preferably threaded at its free end which projects through the lever 59, upon which is mounted a hand-wheel 65, which is bored out centrally and threaded to be screwed onto the pin 64. The object of this threaded connection is to provide means for locking the furnace body 2 in any desired position within the range or length of the slots in the levers 59. When the furnace is in the upright, or charging and firing position shown in Figs. 1, 2 and 3, the hand-wheel 65 may be tightened to hold the body rigid in said position, and when the furnace is tilted to the position shown in Fig. 4, the hand-wheel may again be tightened for holding the furnace in the new position.

The links 44 one of which is connected to the valve 32 and levers 45, extend rearwardly and pivotally connect to the levers 61 intermediate their ends, by pins 44'. The distance from the centers of the pivots 95 of the links 44 is intended to be the same as the distance from the center of the shaft 58 to the center of the shaft 62, which connects the levers 61 to the levers 57, so that when the said parts are operated during the elevation and lowering of the furnace, the corresponding parts are held and moved in parallel relation.

In practice, the molds into which the metal is to be poured are generally so arranged that their pouring vents or sprues come in line alongside and parallel to the tracks 54 on which the furnace is moved from place to place. It frequently happens, however, that some of the sprues are of smaller diameter, and for other reasons, it is impossible to locate all of the molds so that the centers of all of the sprues will be in line parallel to the said tracks, and as the stream of molten metal must flow into the centers of the molds, it is obvious that means must be provided for adjusting the point of the pouring spout 4 to suit the differently located sprues. To this end, I have provided an adjustable mechanism, which comprises the following parts: 66 represents vertically disposed levers pivotally supported by a common shaft 67, which is journaled in the frame parts 14. The lower ends of levers 66 connect with the lower ends of the levers 45 through rods or links 68, by pins 69 and 69'. 70 represents a screw-threaded rod, the outer end of which carries a hand-wheel 70', the inner end thereof being screwed into a yoke 71,

which is pivoted to one of the upright levers 66. The turning of the hand-wheel 70' in the opposite directions, rocks the levers 66 correspondingly, and through the links 68 5 swings the levers 45 on the shaft 58, and thereby correspondingly swings the tops of the levers 61, through the links 44, from the position shown in full lines, to the position shown in dotted lines, in Fig. 6. The adjusting of the levers 61, as described, also effects the shifting horizontally of the levers 59 and the furnace body 2, in the manner and to the extent shown by the full and dotted lines in Fig. 6. The lower ends of the levers 61 are journaled or pivoted to the levers 57, but they are not influenced by the adjustment effected by the operation of the hand-wheel 70', therefore, an increased lateral movement will be imparted to the top ends of the levers 61, to which are pivotally attached the forward arms of the levers 59, which support the top of the furnace body 2, and control the pouring spout 4. In this way the furnace body may be swung forward or backward from the positions shown in full and dotted lines in Fig. 6, and the spout 4 will at the same time be correspondingly shifted in a horizontal direction. This horizontal adjustment will not affect the pouring spout in relation to the other movable parts of the furnace during the pouring operations, and it may be done while the pouring is taking place. The latter result is due to the fact that each of the levers 61 must and will at all times travel or rotate on an axis having the same radius as that which is controlled by the links 44 and the levers 57. The operation of the hand-wheel 70' effects the changing of the axis of the pouring spout horizontally, while the releasing of the hand-wheel 65 permits the furnace body 2 to be tilted and set at any angle within the range or length of the slots 63', which will change the radius from that of the levers 59 and 61, which will permit the spout 4 to move vertically during the elevating and pouring operations.

The operation of the furnace is as follows: When the metal to be poured has been sufficiently heated, the furnace is trundled over the tracks 54, to a position opposite the mold 72, and then the body 2 of the furnace is tilted, preferably by hand; into the position shown in Fig. 4. The metal is then skimmed in the usual manner and is ready for pouring. In case the point of the pouring spout does not come in the right position in relation to the sprue of the mold, the furnace may be adjusted horizontally by the operation of the hand-wheel 70', as explained. If the spout 4 is required to be elevated for positioning the same at a greater or less distance above the top of the mold, this may be accomplished by re-

leasing the hand-wheel 65, by unscrewing the same on the pin 64. The top of the furnace may be slightly elevated or lowered, by moving the pins 64 and 64' toward or away from the forward ends of the slots 70 63', as indicated by the dotted lines in Fig. 5. Then by tightening up the hand-wheel 65, the furnace when elevated from the position shown in Fig. 4 to that shown in Fig. 5, will pour the metal from the desired level. 75 As soon as the pouring spout is adjusted to properly pour the metal into the mold, the operator should grasp the hand-lever 48 attached to the valve 32, and move it toward the left, or downwardly (see Figs. 5, 6 and 9) in a gradual manner. This will cause the rotation of the valve casing 40, from the position shown in Fig. 8, to that shown in Fig. 9, which will establish communication between the pipes 46 and the 80 pipes 31 and 31', and allow the compressed air to flow simultaneously into the cylinders 10 of the hoists A and A'. At the same time, the oil ports c—c' and d—d' and the by-pass h of the valve will be opened for 85 the free passage of the oil from the pipes 34—34' to the pipes 35—35'. The air exerting its pressure against the tops of the cylinders 10 of the hoists, will force said cylinders upwardly, while the plungers 11 will 90 be held stationary by the shaft 12. The upward movement of the cylinders 10, through the connections by means of the lugs 9 with the trunnions 7 and 7', will lift the furnace from the position shown in Fig. 4 to that 100 shown in Figs. 5 and 6, and during this upward or rotary movement of the furnace and its related parts, the molten metal will flow from the crucible 3 and gravitate into the mold 72. The upward movement of the 105 cylinders 10, through the lugs 55 and the levers 56 effects the upward movement of the rear ends of the side levers 57, which in turn lift the angular levers 61, to which are connected the forward arms of the levers 59, which are journaled to the trunnions 7 and 7'. The levers 61 are forced to travel in like arcs which are fixed by the links 44, owing to their pivotal connections with the levers 45. The levers 59 thus form 115 members of what is commonly known as a parallel motion, on account of the radius of the links 44, and the distance between the centers 58 and 62 being the same, by which the levers 59 describe the same arcs. The 120 upwardly projecting ends of the levers 61 connecting with the forward arms of the levers 59, are so disposed as to travel in arcs, the axes of which would normally pass through the tip of the pouring spout 4. 125 The continuation of the upward movement of the cylinders 10 of the hoists will cause all of the levers just described to travel in arcs relative to the point of the pouring spout, whether the point is absolutely fixed 130

or not. If, at any time during the pouring operation, it is desired to increase the height from which the melted metal is to be poured from the point of the spout 4 relatively to the top of the mold, the hand-wheel 65 may be loosened by unscrewing it on the stud or pin 64, and the furnace may then be rocked backwardly or forwardly, as the case may be, on the trunnions 7 and 7', during which movement, the pins 64 and 64' will travel in the slots 63' of the levers 59. Then by screwing the hand-wheel tight again, the furnace will be held in the adjusted position, and the subsequent pouring will be done from a gradually increasing height, until the furnace is emptied, or the mold is filled. After the furnace is emptied, the outer member 40 of the valve 32 should be rotated to the right, by means of the handle 48, from the position shown in Fig. 9 to that shown in Fig. 10, which will allow the air pressure contained in the two hoists to exhaust through the ports *j* and *k* located in the plug 42. As soon as the air is exhausted, the weight of the different parts, including the object hoisted, as the furnace, will force the cylinders 10 downwardly over the plungers 11 to the closed position shown in Figs. 1, 2, 3, 4, and also as shown by the full lines in Fig. 7. When the mold has been filled, and the operation known as "feeding" is commenced, the point of the pouring spout 4 is raised in a gradual manner a suitable distance by the following means: In the first place, the furnace body 2 is released from the locked contact through the pins 64 and 64', and the hand-wheel 65, with the levers 59, by unscrewing the said wheel, as explained. The furnace may then be swung on the trunnions 7 and 7', to a new position, as for example, from the position shown in full, to the position shown in dotted lines, in Fig. 5, which shows the point of the spout 4 in a slightly elevated position. As the furnace is elevated for pouring the metal, the point of the spout 4 will gradually rise in a true vertical line, and the melted metal will fall into the mold from an increasing height with greater force, which is desirable during the feeding operation. The increased force of the gravitating metal will break through the crust which invariably forms on the top of the metal which has been poured, as soon as the casting begins to cool and shrink. Unless this crust is kept broken up, the top end of the ingot or casting will be imperfect, and unless the so-called "feeding" operation is carried out until the mold is entirely full, the ingot will be imperfectly formed, due to checks and flaws and initial strain, which will render it unfit for use. The adjusting of the furnace by means of the pins 64 and 64' and the slots 63', as explained, will cause the point of the pouring

spout, when the furnace is afterward rotated, to move away from the axis or center of the arc described by the tops of the levers 61, which control the levers 59, and will effect the movement of the point of the spout in an arc around the said axis as a center, and the radius of this arc will be the distance that the spout has been moved from the axis of the levers 61. This feature is of great advantage, as when pouring molds of known capacity, this distance may be regulated and fixed so that when the molds have been filled and the feeding operation is begun, the point of the pouring spout will be automatically raised to the desired height without further attention or adjustment by the operator. The subsequent rotation of the furnace on the trunnions 7 and 7' will not affect or change the axis or point of oscillation last described, which will remain in a position governed by the disposition of the levers 61, which in turn are controlled by links 44, and the shafts 58 and 62 on levers 57.

73 represents a spring, which connects at one end by means of screws 75 to the valve casing 40, the opposite end being disposed loosely between pins 74 carried by the link 44. When the casing 40 of the valve is rotated in either direction, the spring 73 is bent (see Figs. 9 and 10) and exerts its tension for rotating the casing in the opposite direction from which the operator moved it. The object of the spring 73 is to prevent the air pressure from continuing to operate the hoists, in case the operator, for any reason, lets go the handle 48, after he has once opened the valve.

When the valve has been opened by the operator, the air pressure actuates the cylinders 10 of the hoists, and these through the levers 56, 57 and 61 will lift the link 44, which is rigidly connected to the plug 42, which rotates with the said link. In case the operator opens the valve part way, by means of the handle 48 and then holds the handle still, after a few seconds' time, the link 44 will have moved upwardly with the lever 61, and will rotate the plug of the valve in the same direction in which the operator turned the casing 40, which will close the valve. In order to prolong the hoisting operation of the hoists, the operator must continue to slowly swing the handle 48 and thus keep time with the rotation of the plug 42 and the link 44, otherwise, the link will close the valve and shut off the air pressure, which will stop the elevating of the furnace.

Having thus described my invention, what I claim as new and desire to secure by Letters Patent, is—

1. In combination, a tiltable and rotatable furnace mounted on trunnions, a pair of fluid pressure actuated hoists for supporting

and operating the furnace, an elevating mechanism for rotating the furnace during the pouring operations, and a valve carried by parts of said elevating mechanism adapted to control said hoists.

2. In combination, a pair of fluid pressure actuated hoists, a rotatable furnace having trunnions journaled to said hoists, means for rocking the furnace on the trunnions, a valve for controlling said hoists, an elevating mechanism coöperating with said hoists for rotating the furnace after the same has been rocked on the trunnions, the said mechanism supporting said valve, and adapted to automatically close the valve whenever the operator is inattentive.

3. In combination, a rotatable furnace mounted on trunnions, a pair of fluid pressure actuated hoists for supporting and rotating said furnace, a valve for controlling said hoists, means for operating said valve for effecting the hoisting of said furnace, and means actuated by said hoists for automatically closing said valve.

25 4. In combination, a furnace mounted on trunnions and having a pouring spout, means for tilting said furnace for bringing the pouring spout into pouring position, locking means for holding said furnace in position for pouring the metal at a fixed point, and adjustable means for effecting the pouring of the metal from different points.

35 5. In combination, a furnace mounted on trunnions and provided with a pouring spout, a pair of power hoists for supporting and operating said furnace, a valve for controlling said hoists, a mechanism for tilting said furnace around an axis passing transversely through the point of the pouring spout, and means for adjusting said furnace for depositing the melted metal at different points.

45 6. In combination, a furnace mounted on trunnions and provided with a pouring spout and an adjustable pouring center, pins carried by the furnace in line vertically with the trunnions, levers journaled to the trunnions having slotted arms to receive said pins, and means for rocking the furnace on the trunnions to move said pins along said slots, for adjusting the pouring spout for pouring metal from different levels for "feeding" the molds.

55 7. A furnace structure comprising a furnace body mounted on trunnions, said furnace body provided with a pouring spout, and with pins in line parallel with a transverse axis passing through the point of the pouring spout, levers journaled to said trunnions having slots in which said pins are adapted to reciprocate when the furnace body is rocked on said trunnions, a hand-wheel for locking the furnace body in a number of positions for pouring the metal

from different levels, and means for elevating and rotating the furnace body on said trunnions.

8. A furnace structure comprising a furnace body mounted on trunnions, and provided with a pouring spout, a pair of fluid pressure actuated hoists for elevating and rotating the furnace body around an axis passing transversely through the point of the pouring spout, and means for adjusting and setting the furnace body, so that when said body is rotated, the pouring spout will move upwardly away from the mold, for pouring the metal from a constantly changing level during the "feeding" of the mold.

70 9. In combination, a furnace body mounted on trunnions, said furnace body having a pouring spout, and having pins in line vertically with said trunnions, said furnace body capable of being rocked on the trunnions for bringing the pouring spout over a mold, levers journaled to said trunnions having arms provided with slots for engaging said pins, a hand-wheel carried by one of said pins for locking the furnace body 85 in different positions when rocked, and a pair of fluid pressure actuated hoists journaled on said trunnions adapted for tilting the furnace body upon said pins.

95 10. In combination, a furnace mounted on trunnions and provided with a pouring spout, pins carried by the furnace, levers journaled to the trunnions having slotted arms to receive said pins, means for rocking the furnace on the trunnions to move said pins along the slots of said levers for adjusting the pouring spout for pouring the metal from different levels for "feeding" the molds, and a pair of fluid pressure actuated hoists journaled to said trunnions, 100 adapted to elevate and rotate said furnace on said pins.

110 11. In combination, a furnace mounted on trunnions having a pouring spout and a pouring axis on a line passing transversely through the point of the pouring spout, elevating means for tilting the said furnace around the pouring axis, and means for adjusting and setting the pouring spout for pouring the metal from different levels for 115 "feeding" the molds.

120 12. In combination, a furnace body mounted on trunnions having a pouring spout and a pouring axis on a line passing transversely through the pouring spout, elevating means comprising a pair of fluid pressure hoists journaled to said trunnions adapted for tilting the furnace body around the pouring axis, and a mechanism actuated by said hoists adapted for normally holding the 125 pouring spout on the pouring axis.

13. In combination, a furnace body mounted on trunnions having a pouring spout and a pouring axis on a line passing transversely through the point of the pouring

- spout, elevating means comprising a pair of fluid pressure actuated hoists journaled to said trunnions adapted for tilting the furnace body around the pouring axis, a mechanism actuated by said hoists adapted for adjustably holding the pouring spout on the pouring axis, and a wheeled-truck for supporting the furnace body and the hoists and for rendering the same portable.
14. In combination, a tiltable furnace mounted on trunnions, a pair of fluid pressure actuated hoists for supporting and operating said furnace, means for braking and steadyng said hoists and said furnace for preventing intermittent movements of said parts, a mechanism connected with and actuated by said hoists, adapted to coöperate with said hoists for elevating and rotating said furnace for pouring metal directly into a mold, a valve carried by parts of said mechanism adapted to control said hoists, and means for automatically closing the said valve when the operator becomes careless or inattentive.
15. In combination, a furnace mounted on trunnions and provided with a pouring spout, a fluid pressure actuated hoist journaled to each of said trunnions for supporting said furnace, a truck frame having wheels for rendering said furnace portable, a shaft carried by said frame for supporting said hoists, means for operating said hoists simultaneously for elevating said furnace for pouring the metal directly into the molds, and means for adjusting the furnace for depositing the metal at different points.
16. In combination, a furnace body mounted on trunnions having a pouring spout and a pouring axis on a line passing transversely through the point of the pouring spout, elevating means comprising a pair of fluid pressure hoists journaled to the trunnions adapted for tilting the furnace body around the pouring axis, a mechanism actuated by said hoists adapted for normally holding the pouring spout on the pouring axis, and means for adjusting parts of said mechanism for varying the pouring axis.
17. In combination, a furnace mounted on trunnions and provided with a pouring spout, a fluid pressure actuated hoist journaled to each of the trunnions and provided with means for preventing intermittent movement thereof, pins carried by the top of the furnace, levers journaled to the trunnions and provided with slotted arms adapted to receive said pins, means for tilting said furnace on the trunnions a distance equal to the travel of said pins in said slots for bringing the pouring spout over a mold, and means carried by one of said pins for locking the furnace in a number of positions intermediate the ends of said slots for effecting the pouring of the metal from different elevations for "feeding" the molds.
18. In combination, a self-contained furnace, a pair of hoisting cylinders for supporting the furnace, a truck-frame for supporting said cylinders, trunnions carried by the furnace for pivotally connecting the furnace to said cylinders, a valve for controlling a fluid pressure for operating said cylinders, means for manually operating said valve, an elevating mechanism connecting to and actuated by said cylinders, parts of said mechanism supporting said valve and adapted to automatically close the valve, and a series of levers and links adapted to operate in parallel relation, for fixing the normal axis around which the furnace rotates.
19. In combination, a tiltable or rotatable furnace body having a pouring spout, a pair of hoisting cylinders for supporting the weight of the furnace and for rotating the furnace body for pouring metal directly into a mold, a mechanism actuated by and coöperating with said cylinders for rotating the furnace around an axis passing transversely through the point of the pouring spout, and a series of links and levers capable of being adjusted for successively changing the axis around which the furnace rotates.
20. In combination, a tiltable or rotatable furnace body having a pouring spout, a pair of hoists for supporting the weight of the furnace body and for rotating the furnace for pouring metal directly into a mold, a mechanism actuated by and coöperating with said hoists for rotating the furnace around an axis passing transversely through the point of the pouring spout, means for adjusting parts of said mechanism for shifting the axis of the pouring spout for depositing the metal at different points, and means for changing the radius of the pouring spout, for effecting the pouring of the metal from different points vertically.
21. In combination, a rotatable furnace mounted on trunnions and provided with a pouring spout, a pair of fluid pressure hoists journaled to the trunnions adapted to support the weight of the furnace and to tilt the furnace for pouring metal directly into molds, levers journaled to the trunnions and provided with slotted arms, said levers adapted to control the arc through which the pouring spout rotates, pins carried by the furnace normally positioned in the slots of said levers adapted to support the top of the furnace during the pouring operations, and means for adjusting and locking said pins in different positions in said slots for changing the radius of the arc through which the pouring spout travels while the furnace is being tilted or elevated.
22. In combination, a furnace mounted on trunnions and provided with a pouring spout and an adjustable pouring center, a fluid pressure actuated hoist journaled on

each of said trunnions, pins carried by the top of the furnace, levers journaled to the trunnions and provided with slots adapted to receive said pins, means for tilting the furnace on the trunnions a distance equal to the travel of the pins in the slots for bringing the pouring spout over a mold, a mechanism adapted to coöperate with said hoists for rotating the furnace on the trunnions and also on said pins, said mechanism arranged to normally hold the pouring spout at a fixed point horizontally, and means connected with said mechanism for shifting and holding the pouring spout at different points horizontally.

23. In combination, a furnace mounted on trunnions and having a pouring spout, a pair of fluid pressure actuated hoists journaled to the trunnions for supporting the weight of the furnace and for tilting the

furnace for pouring the metal, levers journaled to the trunnions having slots, pins carried by the furnace normally positioned in the slots of said levers adapted to support the top of the furnace when tilted, an elevating mechanism connecting with the said hoists and also with said levers, the said mechanism actuated by said hoists, and adapted to fix and control the axis around which the furnace is tilted, and means for adjusting parts of said mechanism for elevating the pouring spout during the pouring operations. 25

In testimony whereof I affix my signature in presence of two witnesses.
